UNITED STATES PATENT OFFICE.

SAMUEL THOMPSON, OF ENGLEWOOD, ILLINOIS.

FOUNTAIN BRUSH AND SPONGE HOLDER.

SPECIFICATION forming part of Letters Patent No. 397,670, dated February 12, 1889.

Application filed February 24, 1888. Serial No. 265,135. (No model.)

To all whom it may concern:

Be it known that I, SAMUEL THOMPSON, of Englewood, in the county of Cook and State of Illinois, have invented a new and Improved 5 Fountain-Brush, of which the following is a specification, reference being had to the annexed drawing, forming a part thereof, which is a transverse section of the head for holding brushes or sponges.

10 My invention relates to improvements in that class of brushes in which the water is conveyed to the place of use through the tubular handle of the brush.

The invention consists in the peculiar construction and arrangement of parts, as hereinafter fully described, and pointed out in the 15 claims.

The inner wall, A, and the outer wall, B, of the holder inclose between them a space, a, 20 for receiving water from the tubular handle inserted in the internally-threaded neck b. The holder is preferably made circular in form, and in the center of the inner part there is a threaded aperture, c, for receiving the 25 nozzle C and other attachments, presently to be described.

The cavity D in the center of the holder is larger at the top than at the bottom, and the nozzle C is externally threaded to receive the 30 circular brush E, having the beveled edge d, fitted to the inclined walls of the cavity D. In the edge of the double wall of the holder are formed series of holes e for the escape of

water from the head to the brush. The periphery of the head is provided with a flat 35 rubber band, F, which projects beyond the edge of the holder and protects the object being washed from contact with the metal part of the head. The rubber band is held in place by a flange formed on the back of the head 40 and projecting beyond its periphery.

Having thus described my invention, I claim as new and desire to secure by Letters Patent—

1. A head for fountain-brushes provided with the inner and outer walls, A B, the central cavity, D, the nozzle C within the cavity, and the handle-receiving neck b, substantially 45 as described.

2. A head for fountain-brushes provided with the inner and outer walls, A B, the apertures e, the central cavity, D, the nozzle C, projecting from the bottom of the cavity, and the threaded handle-receiving neck b, substantially 50 as herein shown and described.

3. In a fountain-brush, the combination, 55 with the hollow head provided with the inner and outer walls, A B, the threaded neck b, the threaded aperture c, and the apertures e, of the externally-threaded nozzle C, and the brush E, received on the nozzle C, substantially 60 as described.

SAMUEL THOMPSON.
